**NON-HYDRATED FERROUS FUMARATE AND
HEMATINIC COMPOSITION THEREOF**

Hugh C. Bertsch, St. Louis, Mo., and John F. Lemp, Alton, Ill., assignors to Mallinckrodt Chemical Works, St. Louis, Mo., a corporation of Missouri

No Drawing. Application May 18, 1956
Serial No. 585,633

12 Claims. (Cl. 167—68)

This invention relates to compounds of iron and more particularly to ferrous salts of organic acids.

Briefly, this invention is directed to non-hydrated ferrous fumarate and to methods of preparing it. The invention also includes new hematinic compositions and animal feed supplements, as well as methods of treating human beings and domestic animals.

Among the objects of this invention may be mentioned the provision of a new compound of iron; the provision of a useful hematinic; the provision of a compound of the type indicated which has a high iron content and is substantially nontoxic; the provision of a new and pharmaceutically useful ferrous compounds; the provision of such a compound which is substantially tasteless; the provision of such a compound which is easily prepared relatively free of ferric iron and in substantially anhydrous form; the provision of such a compound which is not readily oxidized upon exposure to air; the provision of such a compound which is relatively stable upon exposure to moist air; the provision of new pharmaceutical compositions containing iron; the provision of methods of preparing anhydrous ferrous fumarate; and the provision of methods for treating both human beings and domestic animals suffering from a deficiency of iron. Other objects and features will be in part apparent and in part pointed out hereinafter.

The invention accordingly comprises the products and methods hereinafter described, the scope of the invention being indicated in the following claims.

The use of iron preparations in the treatment of certain anemias is well established. Ferrous salts were generally preferred for this purpose since it is widely accepted that ferrous iron is more readily absorbed from the gastrointestinal tract of man than is ferric iron.

However, the pharmaceutically useful ferrous iron salts previously known, such as ferrous sulfate, ferrous gluconate, and ferrous lactate, suffer from one or more of the following disadvantages: instability in air with regard to oxidation and/or changes in color or moisture content; and low iron content; unpleasant taste; and gastrointestinal irritability.

In accordance with the present invention it has now been found that an anhydrous or non-hydrated salt of ferrous iron and fumaric acid may be readily prepared and that its surprisingly advantageous properties make it particularly useful as a hematinic. The novel anhydrous ferrous fumarate compound of the present invention is a free-flowing dark brown to reddish-brown granular powder. The color varies with the method of preparation, the preferred product being reddish-brown. Its empirical composition corresponds to the formula

representing about 33% iron. The exact nature of its structure is not known at this time. However, some of its properties, for example, its brown color and its resist-

2

ance to oxidation are not typical of a simple ionic ferrous salt. X-ray diffraction studies by the powder method indicate that its structure is crystalline, as numerous sharp lines are observed in the diffraction pattern.

5 While ferrous fumarate trihydrate has been previously prepared, it is no more stable than the heretofore well-known ferrous salts. In contrast, the novel anhydrous ferrous fumarate of this invention remains relatively free flowing and shows little tendency to oxidize or hydrate even during several weeks' exposure to a hot humid atmosphere.

Because anhydrous ferrous fumarate is substantially tasteless it may conveniently be administered in uncoated tablets, while tablets of other iron salts must ordinarily be coated to eliminate the objectionable "iron taste." Also, anhydrous ferrous fumarate does not noticeably irritate the gastrointestinal tract.

The anhydrous ferrous fumarate of this invention is readily prepared by slowly mixing hot solutions of sodium fumarate and ferrous sulfate, whereupon the sparingly soluble anhydrous ferrous fumarate precipitates. While it is preferable that the precipitation be made at a temperature above approximately 94° C. it may be made at any temperature from approximately 70° C. to the boiling point of the solution in which the precipitation is made. Although a suitable product may be prepared by adding the ferrous sulfate solution to the sodium fumarate solution, adding the sodium fumarate solution to the ferrous sulfate solution produces a product containing a smaller proportion of occluded sodium salts. It is substantially free of ferric iron and remains so upon further handling without being specially protected from contact with air. A suitable product may also be made using a slurry of sodium fumarate rather than a solution. Such a slurry may occur if the sodium fumarate is made up in a volume of water that is insufficient to dissolve all the salt formed.

According to the present invention, ferrous fumarate may be combined with various other materials to give 40 therapeutically useful compositions in dosage form. For example, it may be used in the form of tablets of ferrous fumarate and a carrier (such as fillers, binders, and lubricants), or hard gelatin capsules filled with ferrous fumarate, or other dosage forms particularly useful for oral ingestion.

Examples of solid pharmaceutical carriers include starch, gelatin, talc, stearic acid, magnesium stearate and the like. Examples of binders include liquid glucose, starch paste, acacia solution and gelatin solution. Any of the conventional tabletting materials used in pharmaceutical practice may be employed as carriers herein where such materials are compatible with ferrous fumarate.

When anhydrous ferrous fumarate is administered 55 orally to human patients suffering from an iron-deficiency anemia the rate of hemoglobin regeneration is as satisfactory as that obtained with ferrous sulfate. Moreover, the reticulocyte response is higher and more prompt than usually occurs with iron therapy, and there is no noticeable gastrointestinal discomfort.

60 The following examples illustrate the invention.

Example 1

A solution of sodium fumarate was prepared by slowly adding fumaric acid (41 lb. 2 oz.) to a solution of sodium carbonate (44 lb. $\text{Na}_2\text{CO}_3 \cdot \text{H}_2\text{O}$) in water (44 gal.). The pH was approximately 7. During a period of ten minutes a moderately hot (50° C.) clear solution (22.9 gal.) of ferrous sulfate (90 lb. $\text{FeSO}_4 \cdot 7\text{H}_2\text{O}$) having a pH 70 of 2.4 was added with mixing to the solution of sodium

fumarate, the latter being maintained at a temperature of 94–100° C. during the addition. The resulting slurry of reddish-brown anhydrous ferrous fumarate was stirred for 30 minutes during which its temperature dropped to 53° C. The slurry was then filtered and washed in a centrifuge and the anhydrous ferrous fumarate was dried in trays (115° C. for 17 hours). Yield: 42 lb.—70% of theory. Calculated for $\text{FeC}_4\text{H}_2\text{O}_4$: Fe, 32.9%. Found: Fe, 32.2%. Only 0.5% of ferric iron was found.

Example 2

Sodium carbonate (53.5 lb. of $\text{Na}_2\text{CO}_3 \cdot \text{H}_2\text{O}$) was dissolved in water (40–45 gal.) and fumaric acid (50 lb.) was added slowly. During the addition the solution was stirred and heated. The resulting solution of sodium fumarate, having a pH of 6.8, was added slowly with mixing to a solution of ferrous sulfate (118 lb. $\text{FeSO}_4 \cdot 7\text{H}_2\text{O}$ in 33 gallons of water) having a pH of 3.3, both solutions being maintained at or near boiling temperature during the mixing. The resulting slurry of reddish-brown anhydrous ferrous fumarate was filtered and washed in a centrifuge and dried in a tray drier (15 hours at 110° C.). Yield: 63 lbs.—86% of theory. Calculated for $\text{FeC}_4\text{H}_2\text{O}_4$: Fe, 32.9%. Found: Fe, 32.6%. Only 0.2% of ferric iron (Fe^{+++}) was found.

Example 3

A tablet granulation was prepared by moistening anhydrous ferrous fumarate (7.5 kg.) with a mixture of equal parts of liquid glucose and water (64 fl. oz. of the mixture). Magnesium stearate (1%) was mixed with the dried granulation and the mixture was tableted into tablets each containing approximately 200 mg. of anhydrous ferrous fumarate.

Example 4

Tablets were also prepared containing starch (5%) in addition to the components shown in Example 3. These, while retaining good mechanical strength, had the advantage of disintegrating more rapidly in artificial gastric juice.

Example 5

Two groups of adult male albino rats, each group consisting of six rats, received ferrous sulfate and anhydrous ferrous fumarate, respectively, by stomach intubation. The iron salts were administered daily, five days a week, for two weeks, a total of ten doses. Each compound was administered as a 5% (w/v.) aqueous suspension. The initial dose of each compound contained 36.8 mg. of iron, but subsequent doses were reduced to 18.4 mg. of iron each because of toxic reactions in the control rats which received ferrous sulfate. Food consumption and body weights were measured at weekly intervals. The rats were observed daily for gross signs of systemic toxicity during the dosage period and for one week afterward. Gross autopsies were performed on rats that died. At the end of the observation period the survivors were sacrificed and gross autopsies were performed.

All rats receiving anhydrous ferrous fumarate survived. The average body weights and food consumption were normal and at autopsy all organs appeared normal. Of the six control rats which received ferrous sulfate one died after the second dose and a second died after the fifth dose. The four survivors generally appeared normal after the second day. The average body weights and food consumption were within the normal range and at gross autopsy all organs appeared normal.

Example 6

A portion of anhydrous ferrous fumarate was exposed to the atmosphere at room temperature for six months. A second portion was confined over water in a desiccator at 80° C. for four weeks. The desiccator was closed except while samples were being drawn for analysis, but no attempt was made to exclude air. From time to time,

samples were removed and assayed for ferrous and ferric iron. The results are shown in the following table:

Elapsed Time	Portion I—Room Temperature and Atmosphere		Portion II—80° C. and approximately 100% relative humidity	
	Ferrous Iron (as Fe)	Ferric Iron (as Fe)	Ferrous Iron (as Fe)	Ferric Iron (as Fe)
	Percent	Percent	Percent	Percent
0	31.3	0.8	31.3	0.8
2 days			31.2	0.8
4 days			31.2	0.9
1 week			31.0	0.8
10 days			31.1	1.1
15	31.1	0.6	30.95	0.8
2 weeks	31.1	0.7	30.6	1.0
3 weeks	31.1	0.7	30.8	0.9
4 weeks	31.1	0.7		
6 weeks	31.2	0.7		
2 months	31.1	0.7		
3 months	31.1	0.7		
4 months	31.1	0.7		
20	31.0	0.5		
5 months				
6 months	31.0	0.9		

No change was noted in the appearance of the exposed samples as compared with the unexposed starting material. The sample exposed at 80° C. and about 100% relative humidity for 4 weeks was subjected to X-ray diffraction and the pattern obtained was identical to that of the starting material.

Example 7

30 A portion of anhydrous ferrous fumarate was exposed to air saturated with water vapor at a temperature of 63–65° C. for a period of four weeks. At weekly intervals, samples were withdrawn and assayed for ferrous iron, ferric iron, total iron and moisture content. The 35 results are shown in the following table:

Elapsed Time	Percent H ₂ O	Percent Iron		
		Ferrous	Ferric	Total
40				
0		31.1	0.6	32.2
1 week	0.1	29.2	1.8	31.8
2 weeks	0.7	28.7	3.3	31.7
3 weeks	0.5	28.7	3.3	31.5
4 weeks	0.5		3.4	31.6

45 While we prefer to use sodium fumarate and ferrous sulfate, to prepare anhydrous ferrous fumarate, other water-soluble ferrous salts, such as ferrous chloride and ferrous acetate, and other water-soluble salts of fumaric acid, such as ammonium fumarate and potassium fumarate, may be used, as long as the cation of the fumaric acid salt chosen and the anion of the ferrous salt chosen do not react to form a sparingly soluble compound under the reaction conditions to be used.

50 It will be understood that the term "substantially anhydrous ferrous fumarate" as used herein designates the non-hydrated ferrous salt of fumaric acid having the empirical formula $\text{FeC}_4\text{H}_2\text{O}_4$.

55 In view of the above, it will be seen that the several objects of the invention are achieved and other advantageous results attained.

As various changes could be made in the above methods and products without departing from the scope of the invention, it is intended that all matter contained in the 65 above description shall be interpreted as illustrative and not in a limiting sense.

We claim:

1. Non-hydrated ferrous fumarate.
2. Non-hydrated ferrous fumarate, having the empirical formula $\text{FeC}_4\text{H}_2\text{O}_4$, and characterized by being substantially stable upon exposure to moist air.
3. The method of preparing non-hydrated ferrous fumarate which comprises mixing a water-soluble ferrous salt and a water-soluble salt of fumaric acid in an aqueous medium at a temperature above approximately

70° C. to precipitate substantially anhydrous ferrous fumarate, and thereafter separating the non-hydrated ferrous fumarate from the aqueous medium.

4. The method of preparing non-hydrated ferrous fumarate which comprises mixing a solution of a water-soluble ferrous salt and a solution of a water-soluble salt of fumaric acid at a temperature above approximately 70° C. to precipitate substantially anhydrous ferrous fumarate, and thereafter separating the non-hydrated ferrous fumarate from the solution.

5. The method of preparing non-hydrated ferrous fumarate which comprises mixing a solution of a water-soluble ferrous salt and a solution of a water-soluble salt of fumaric acid at a temperature above approximately 94° C. to precipitate substantially anhydrous ferrous fumarate, and thereafter separating the non-hydrated ferrous fumarate from the solution.

6. The method of preparing non-hydrated ferrous fumarate which comprises mixing a solution of ferrous sulfate and a solution of sodium fumarate at a temperature between approximately 94° C. and the boiling point of the mixture of said solutions to precipitate substantially anhydrous ferrous fumarate, and thereafter separating the non-hydrated ferrous fumarate from the solution.

7. The method of preparing non-hydrated ferrous fumarate which comprises adding a solution of the sodium

um salt of fumaric acid to a solution of ferrous sulfate at a temperature between approximately 94° C. and the boiling point of the mixture of said solutions to precipitate substantially anhydrous ferrous fumarate, and thereafter separating the non-hydrated ferrous fumarate from the solution.

8. A hematinic composition in dosage form, comprising non-hydrated ferrous fumarate and a pharmaceutical carrier.

10. 9. A hematinic composition in dosage form, comprising a major amount of non-hydrated ferrous fumarate and a minor amount of a pharmaceutical carrier.

10. A hematinic composition in tablet form, comprising a major amount of non-hydrated ferrous fumarate and a minor amount of magnesium stearate.

11. A process for treating an iron-deficiency anemia which comprises orally administering non-hydrated ferrous fumarate to an animal.

12. A process for treating an iron-deficiency anemia which comprises orally administering non-hydrated ferrous fumarate in tablet form to an animal.
